DESIGN.

—o—

R. F. DOHERTY.
CARPET.

No. 20,752.

Patented May 19, 1891.

UNITED STATES PATENT OFFICE.

ROBERT F. DOHERTY, OF YONKERS, NEW YORK, ASSIGNOR TO THE ALEX. SMITH & SONS CARPET COMPANY, OF SAME PLACE.

DESIGN FOR A CARPET.

SPECIFICATION forming part of Design No. 20,752, dated May 19, 1891.

Application filed April 22, 1891. Serial No. 390,045. Term of patent $3\frac{1}{2}$ years.

To all whom it may concern:

Be it known that I, ROBERT F. DOHERTY, a subject of the Queen of Great Britain, residing at Yonkers, Westchester county, New York, have invented a new and original Design for Carpets, of which the following is a specification, reference being had to the accompanying photograph, which forms a part of the same.

10 The invention relates to a design to be worked into or upon surfaces, such as carpets or similar fabrics; and it consists in the novel configuration and grouping of figures herein specifically shown and claimed.

15 The accompanying photograph is a face view of a carpet, showing my new design.

My design consists of the body A and the border B. The body A consists of highly-ornamented and conventionalized somewhat 20 scroll-shaped forms entwining an ornamental

form decorated with flower forms upon a shaded ground. The border B consists of spirally-arranged stem, flower, and leaf forms upon a somewhat shaded ground, of an inner serrated and decorated margin, and of an outer serrated marginal decoration of contrasted shading.

What I claim as new, and desire to secure by Letters Patent, is—

1. The design for carpets, consisting of the body A, substantially as shown.

2. The design for carpets, consisting of the border B, substantially as shown.

3. The design for carpets, consisting of the body A and the border B, substantially as shown.

ROBERT F. DOHERTY.
